UNITED STATES PATENT OFFICE.

OLIN A. SARGENT, OF BROOKLYN, NEW YORK, ASSIGNOR TO THE FRASER TABLET COMPANY, A CORPORATION OF NEW YORK.

DISPLAY-EASEL.

1,058,794.

Specification of Letters Patent.

Patented Apr. 15, 1913.

Application filed July 15, 1912. Serial No. 709,551.

To all whom it may concern:

Be it known that I, OLIN A. SARGENT, a citizen of the United States, residing at Brooklyn, in the county of Kings and State 5 of New York, have invented or discovered certain new and useful Improvements in Display-Easels, of which the following is a specification, reference being had therein to the accompanying drawings.

10 This invention relates to a box or easel for holding and displaying small articles of merchandise, such, for example, as packages of confectionery or the like, upon the counters of stores, and in similar places.

15 The invention has for its objects to provide a device of this character which will be of a light, simple, and inexpensive construction, which will be capable of displaying the goods, and also, if desired, advertising matter used in connection therewith, in an attractive manner, and which will permit said goods to be conveniently dispensed therefrom when sold. These and 20 other objects of the invention, together with

25 means whereby the same may be carried into effect, will best be understood from the following description of one form or embodiment thereof illustrated in the accompanying drawings, in which:

30 Figure 1 is a perspective view showing the device in use and with the articles of merchandise in place therein. Fig. 2 is a central vertical section with the articles removed. Fig. 3 is a horizontal section taken 35 substantially on the line 3—3, Fig. 2.

The device comprises a receptacle for containing the articles of merchandise 20, said receptacle preferably having both its front and top open, as shown, together with means 40 for supporting said receptacle in an inclined position. The receptacle and supporting means may be constructed of any suitable material, such as wood, sheet metal, or the like, but will preferably be formed 45 from cardboard or similar light sheet material.

In the construction shown the receptacle comprises a back portion 12, an integral bottom portion 13 folded forwardly from said 50 back portion, and integral side portions 14 also folded forwardly from said back portion 12. The side portions 14 are secured at their lower ends to the bottom portion 13, this being accomplished in the construction 55 shown by folding the lower edges 15 of

said side portions beneath said bottom portion, and attaching the same thereto by any suitable means, such as staples 16. The side portions 14 are preferably of less length than the back portion 12, permitting the 60 latter to be extended above the receptacle proper, as indicated at 17, said part 17 being a stiff standing portion which provides a space for advertising matter, or for such other purpose as may be desired. 65

As herein shown the means for supporting the receptacle comprises separate supporting webs 18, formed from separate pieces of material and rigidly secured to the side portions 14 of the receptacle in any suitable 70 manner, as by means of glue or other adhesive. In order to provide for supporting the receptacle in an inclined position the lower edges 19 of said webs 18 are inclined to the back and bottom portions 12 and 13, 75 respectively, of said receptacle, or are so cut or shaped as to form acute angles with both of said portions.

From the foregoing it will be understood that the improved display box or easel consists of only three pieces of sheet material. The body of the box or easel, with its open front and top, and its upwardly extended back 17, is formed from a single piece of material in that the bottom 13 and the side 80 portions 14 are bent or extended forward from the back, at right angles thereto, with the lower ends 15 of the said side portions bent inwardly so as to be parallel with the said bottom and attached to said bottom 85 to support the latter; while the support for the box comprises the two outer side pieces or webs 18 secured to said side portions 14 and having inclined lower edges and rear extensions terminating at their lower ends 90 some distance back of the body of the box, to support the latter in a backwardly inclined position. 95

By reason of the inclined position of the receptacle the articles contained therein are 100 suitably supported and retained by the back, side, and bottom portions thereof, so that the top and front of said receptacle may be left open, as above described, in order effectively to display the contents and to 105 permit the ready removal thereof. Moreover the supporting webs 18, being rigidly secured to the side portions 14, form a convenient means for firmly supporting the receptacle in the desired position without 110

the possibility of overturning, and may, as above explained, be formed of the same material as the receptacle. Furthermore the upwardly extended portion 17 of the back 5 12 provides a convenient space for the display of advertising or explanatory matter not appearing with the desired prominence upon the articles themselves, or for the exhibition of any other device designed to attract the attention of possible purchasers.

Having thus described my invention I claim and desire to secure by Letters Patent:

15 A display box or easel having an open front and top and comprising only three pieces of sheet material, the body of the device consisting of a back portion 12, a bot-

tom 13 and side portions 14 integral with and extending forward from said back portion at right angles thereto, the lower edges 20 15 of said side portions being bent inwardly parallel with said bottom and attached thereto, and outer side pieces 18 attached to said side portions 14 and having inclined lower edges and rearward extensions terminating 25 at their lower ends some distance back of the body of said box to support the latter in an inclined position.

In testimony whereof I affix my signature, in presence of two witnesses.

OLIN A. SARGENT.
